CLAIM

The ornamental design for a jump rope handle, as shown and described.

DESCRIPTION

FIG. 1 is a front, and top perspective view of a jump rope handle, showing my new design;

FIG. 2 is a rear, and bottom perspective view thereof;

FIG. 3 is a front view thereof;

FIG. 4 is a rear view thereof;

FIG. 5 is a left side elevation view thereof;

FIG. 6 is a right side elevation view thereof;

FIG. 7 is an enlarged top plan view thereof; and,

FIG. 8 is an enlarged bottom plan view thereof.
